UNITED STATES PATENT OFFICE.

LAWRENCE E. McALLISTER, OF BELLAIRE, OHIO.

METHOD AND APPARATUS FOR DETERMINATION OF MOISTURE IN SOLID MATERIALS.

1,347,106.

Specification of Letters Patent.

Patented July 20, 1920.

Application filed May 8, 1919. Serial No. 295,648.

To all whom it may concern:

Be it known that I, LAWRENCE E. McALLISTER, a citizen of the United States, and residing at Bellaire, Ohio, have invented 5 certain new and useful Improvements in Methods and Apparatus for Determination of Moisture in Solid Materials, of which the following is a specification.

The present invention relates to means for 10 and a method for determination of moisture in solid materials and more particularly to an apparatus whereby such determinations may be made accurately and quickly.

Heretofore in the determination of moisture in solid materials such as coal, charcoal and other finely granular materials, the procedure has been to weigh as accurately as possible a small sample of the material and place in an oven which may be heated to 20 temperatures somewhat above the boiling point of water and dry the sample in this oven, keeping the temperature as nearly uniform as possible, until the sample shows a constant weight.

25 The accuracy of this procedure is in a great many cases questionable, due to the volatility of certain other constituents than moisture and involves the use of more or less expensive apparatus for controlling the 30 temperature of the ovens and takes considerable time for each determination. The time used in this operation, while depending to a great extent upon the character of the material, is, nevertheless, seldom less than 35 several hours.

The present invention is designed to overcome a number of difficulties connected with the above method and has among its objects a process and apparatus for making moisture 40 determinations quickly, accurately, and without the use of complicated and expensive apparatus.

As the present invention was made particularly to take care of the determination 45 of moisture in producing activated charcoal, the following description will be based upon such determinations, although it will be clear that the method and apparatus are not limited to determining moisture in charcoal, as it may undoubtedly be used with advantage in determining the moisture content of any solid material, which will not pack so tightly in the apparatus as to prevent the passage of air through a short 50 column thereof.

The invention will be more readily de-

scribed and understood by reference to the accompanying drawings in which:

Figure 1 shows an apparatus suitable for carrying out the method. 60

Fig. 2 shows a chart upon which have been plotted certain curves which follow a definite law hereafter given and by reference to which the percent of moisture may be found. 65

Fig. 3 is a similar chart the purpose of which is hereafter explained.

Referring now particularly to Fig. 1, of the drawings, a column of charcoal (1) is placed in tube (2) and supported therein on the 70 gauze or perforated plate (3) so as to allow passage of air longitudinally of the column. The upper end of tube (2) is closed by means of a tightly fitting stopper (4) provided with two holes through one of which extends a thermometer (5) having the bulb imbedded in the column of charcoal. Through the other hole in stopper (4) extends a pipe (6) provided with valve (7) which opens into the upper end of tube (2) 75 above the surface of the charcoal and which is connected at its other end to a pipe (8) leading from a tube (9) which in the form illustrated is shaped like an ordinary test tube. The tube (9) has tube (10) leading 80 therefrom near the top. 85

The tube (9) is also closed at the top by means of a tightly fitting stopper provided with two holes through one of which the pipe (8) extends to a point near the 90 lower end and through the other of which is inserted a thermometer (11) the bulb being also placed near the lower end of tube (9). Connected with the side tube (10) is a series of flasks (12) containing suitable 95 drying material such as sulfuric acid and provided with the means for stopping entrained acid. This series of flasks may be two or more in number having acid in the first one or more and having in the one adjacent to (9) a material such as glass wool or some similar material to act as a baffle for entrained acid. The first of the flasks is provided with an entrance for air such as funnel tube 18 in which is placed a filter 100 plug of glass wool or cotton or other suitable material to remove dirt from the entering air. 105

Connected to the lower end of tube (3) is a pipe (13), which leads back to pipe (8) 110 and is provided with a valve (17) while there is also a valve in pipe (8) between the points

of connection therewith of pipes (13) and (6), the valve referred to being numbered (16) on the drawing. By this arrangement it will be readily seen that the portion of pipe (8) containing valve (16) may be used as a by-pass.

Pipe (8) is in turn connected at (15) with an apparatus for producing vacuum and is also provided with a flowmeter (14) for determining the rate of flow of air through the apparatus.

In the preferred method of operation the tube (2) is about 2 cm. in diameter and the column of charcoal 10 cm. long, having the bulb of the thermometer (5) so placed that the center of the bulb is exactly 3 cm. below the top of the column. While these dimensions have been found suitable and the curves on the accompanying charts plotted to accord with these dimensions, it is obvious that other dimensions may be used and suitable curves plotted. It is, therefore, to be noted that these dimensions are given merely by way of example and the invention is not limited thereto, although the description will proceed as though the apparatus were constructed in this form and operated accordingly.

The principle of the present apparatus is similar to that of the wet and dry bulb hygrometer, that is, it depends upon the lowering of the temperatures produced by evaporation of moisture and it is from the difference in temperatures shown by the two thermometers (5) and (11) when a definite rate of flow of dry air through the apparatus is produced, that the amount of moisture in the sample may be calculated.

In the operation of the apparatus a suitable quantity of the sample is placed in tube (2) in the manner above indicated and suction is applied through the end (15) of pipe (8), valve (16) being closed and valves (7) and (17) open. The rate of flow of air through the apparatus should be accurately regulated according to the amount of sample and the dimensions of the column. Using the dimensions above given this rate of flow should be 7300 cc. of air per minute.

When the suction is applied to pipe (8) in the manner mentioned, air enters the inlet (18) at the end of the series of flasks and passing through the drying material therein, becomes entirely deprived of its moisture. Passing from the flasks it enters the tube (9) and its temperature may be ascertained by means of thermometer (11) immediately before it enters the sample (1). When the air passes through sample (1) evaporation of moisture is produced and due to the evaporation there is a corresponding lowering of the temperature. This decrease in temperature is indicated by thermometer (5).

Upon continued passage of the air

through the apparatus it will be noted that while the air in tube (9) remains at practically a constant temperature, the temperature shown by thermometer (5) will rapidly fall and after a while begin to rise from its 70 lowest point. The minimum temperature in the sample should be carefully noted. As the sample in the first instance is at room temperature or should be, the drop in temperature is an indication of the moisture content so that with the two readings the percentage of moisture may be readily determined.

The accompanying chart shown in Fig. 2 is based upon the dimensions of tubes and 80 sample herein given and upon the use of thermometers graduated with a Fahrenheit scale so that with the two readings of the temperature of the sample and the curves and chart in Fig. 2, the percentage of moisture 85 is very readily determined.

An example of the method of using the chart shown in Fig. 2 is as follows: Assuming that the initial temperature of the sample, which as stated above is preferably room temperature, is say 85° F. and that the minimum temperature reached by the sample on operating the method described is 67° F. The difference between these two temperatures is 18°,

$$T-T'=t$$

T=initial temperature.

T'=minimum "

t=change in "

Looking at the chart we find on the left hand margin as ordinate the series of figures indicating the drop in temperature t . Locating the ordinate which corresponds to the particular temperature change assumed, 105 i. e. 18, and following this line to the right until it intersects the curve marked 85° F., i. e. the initial temperature, we find that the abscissa of this point corresponds to 6.6 per cent. moisture as indicated along the 110 lower edge of the chart. These points are indicated on Fig. 2 by letters A, D, and E.

The curves plotted on the chart shown in Fig. 2 were calculated in the following manner:

It was found by a large number of experiments that the dropping temperature in samples in this apparatus was not exactly proportional to the percentage of moisture in the sample, but follows a law expressed 120 in general by the equation—

$$(a) t=AM^n$$

where t equals drop in temperature, M equals percentage of moisture, A is a constant depending on the initial temperature and n being less than one, also depending on the initial temperature.

The effect of the initial temperature is two-fold; viz., at high temperatures the 130

capacity of the air for moisture is greater, while the capacity of the sample for moisture is less. Therefore, if the initial temperature is high, it is evident that more moisture will be given up by the sample and more moisture will be taken up by the air before the saturation point is reached for that temperature, giving a drop in temperature of the sample greatly different than 10 would be obtained if the initial temperature were lower.

In order to determine the effect of the initial temperature, a series of tests were made, varying the temperature as much as 15 possible, and the following empirical equation was derived:

$$(b) M = \log^{-1} \frac{\log t - \log \left(3 + \frac{T-35}{40} \right)}{.055(T-58)^{.504} + 0.47}$$

where

T = initial temperature

t = change in "

M = per cent. moisture in sample.

25 In the general exponential form as above equation (a) becomes

$$t = \left(3 + \frac{T-35}{40} \right) M (0.055(T-58)^{.504} + 0.47)$$

30 where

$$A = \text{the constant} \left(3 + \frac{T-35}{40} \right)$$

$$n = 0.055(T-58)^{.504} + 0.47$$

35 Curve 2 on the chart shown in Fig. 3 gives values of the

$$\log \left(3 + \frac{T-35}{40} \right)$$

40 for different values of T; and

Curve 1 on this same chart gives values of n for different values of T. So, by the use of the equations and curve equation (b) 45 may be used for any temperature. This variation in temperature may be shown encountered in the operation. The chart shown in Fig. 2 shows different graphical representations, thus obviating the use of 50 the equation and enabling the operator to determine the moisture content of a given sample without resorting to calculation.

In the operation of the apparatus and 55 method, it is essential that the sample under treatment be at the same temperature as

the atmosphere surrounding the tube at the time of starting the run. The reason for this is obvious. It is accordingly preferable to prepare several of the sample tubes with the sample therein and allow them to 60 stand for a while in the room where the determination is to be made.

Sometimes, also, during a run the temperature of the charcoal may rise somewhat. This indicates a leak of atmospheric 65 air containing a moisture and is probably caused by condensation or possibly heat absorption.

It is also essential that the drying agent shall be efficient.

Having now described the invention and the preferred method of practising the same, it is to be understood that it is not limited to the specific examples herein given as these may be varied without departing 75 from the spirit of the invention as indicated in the accompanying claims.

Claims:

1. Apparatus for determination of the moisture content of solid material, comprising, in series, means for drying air and determining the temperature of said dry air, means for containing a sample of the material under observation in such fashion as to permit passage of air through the sample, means for determining the change in temperature of the sample, means for determining the rate of flow of air through the apparatus, and means for producing such flow.

2. A method of determining moisture content of solid material comprising producing a flow of dry air through a confined sample of the material and ascertaining the change in temperature produced in said 95 sample by evaporation of moisture therefrom by the passage of the dry air therethrough.

3. A method of determining moisture content of solid material comprising 100 confining a sample of the material within a suitable vessel, producing a definite and uniform flow of dry air through the sample, determining the change in temperature produced by evaporation of moisture from 105 the material, and calculating the moisture content from the change in temperature and the initial temperature.

LAWRENCE E. McALLISTER.

It is hereby certified that in Letters Patent No. 1,347,106, granted July 20, 1920, upon the application of Lawrence E. McAllister, of Bellaire, Ohio, for an improvement in "Methods and Apparatus for Determination of Moisture in Solid Materials," errors appear in the printed specification requiring correction as follows: Page 3, lines 28-29, equation, for the expression $(0.055(T-58)^{.504} + 0.47)$ read $M(0.055(T-58)^{.504} + 0.47)$; same page, line 44, after the word "curve" insert a comma; and that the said Letters Patent should be read with these corrections therein that the same may conform to the record of the case in the Patent Office.

Signed and sealed this 28th day of September, A. D., 1920.

[SEAL.]

M. H. COULSTON,

Acting Commissioner of Patents.
